UNITED STATES PATENT OFFICE.

JOHN W. UPP AND WILLIAM O. WAKEFIELD, OF SCHENECTADY, NEW YORK, ASSIGNEES
TO GENERAL ELECTRIC COMPANY, A CORPORATION OF NEW YORK.

MACHINE FOR WASHING BLUE-PRINTS.

1,008,624.

Specification of Letters Patent. Patented Nov. 14, 1911.

Application filed July 14, 1904. Serial No. 216,527.

To all whom it may concern:

Be it known that we, JOHN W. UPP and WILLIAM O. WAKEFIELD, citizens of the United States, residing at Schenectady, in the county of Schenectady, State of New York, have invented certain new and useful Improvements in Machines for Washing Blue-Prints, of which the following is a specification.

10 This invention relates to apparatus for treating prints made on sensitive paper, which require to be washed in order to develop or fix them. It has special reference to washing blue-prints, which are made in such enormous quantities by many large manufacturing concerns, that devices which facilitate their handling and cheapen the cost of production are very desirable.

The ordinary mode of washing blue-prints is to lay each sheet in a shallow tank and subject it to the action of running water for several minutes, after which it is lifted out and hung up to dry. This necessitates a good deal of manipulation for each separate sheet, and is a slow and costly process.

Our invention enables one operator to wash large numbers of sheets rapidly and thoroughly.

It consists in a conveyer of peculiar construction by which the sheets are carried under a plurality of water-spraying pipes and finally delivered to suitable drying mechanisms.

In the accompanying drawing, Figure 1 is a side elevation, partly broken away, of our improved machine; Fig. 2 is an elevation of a portion of the same, viewed from the opposite side; Fig. 3 is a top-plan view of part of the machine; and Fig. 4 shows a modification.

A frame 1 is suitably supported, as on trestles 2, with one end preferably higher than the other. A plurality of transverse parallel shafts 3 is journaled in bearings in opposite sides of the frame. Each shaft has a sprocket-wheel 4 for driving it, and in order to use sprockets of considerable size and yet bring the shafts near together, the sprockets are arranged alternately in two rows, those in one row overlapping those in the other. At one end of the frame is a transverse driving-shaft 5 provided with two sprocket-wheels 6, each of which is connected by a chain belt 7 with one row of

sprocket-wheels 4. The shaft 5 also has a belt-pulley 8 by which power is communicated to the machine.

On each of the transverse shafts 3 is secured a plurality of disks 9, spaced apart, sufficiently to overlap those on the adjacent shafts without touching them, so that all can turn freely. In Fig. 3 only two shafts are shown furnished with a complete set of disks, but in practice all the shafts are fully equipped therewith. The tops of this bank 60 of disks form a nearly level bed on which blue-prints or other sheets to be treated can rest and along which they will be conveyed by the rotation of the disks, as they all rotate in the same direction.

Above the conveyer is a grid of perforated water pipes 10, supported on rails 11, and projecting numerous jets of water upon the prints as they are carried under them, face upward. The prints are fed in at the 75 lower end of the frame, so that the water drains backward from them and they are subjected to fresh supplies as they move upward. Arriving at the higher end of the conveyer, they are drawn off by a small, 80 rapidly revolving roll 12 driven by a belt 13 from a pulley 14, and are received by an endless traveling apron 15 of a drying machine. The pulley 14 is a little larger than the disks 3, so that the small roll is driven 85 at a higher peripheral speed than the disks. The result is that the prints are pulled off the conveyer, and any wrinkles are thereby smoothed out.

In Fig. 4, the driving sprockets remain 90 all of the same size, but the disks increase slightly in diameter from shaft to shaft, so that the resulting increase in the peripheral speed of the disks exerts a constant pull on the prints and keeps them smooth 95 and un wrinkled.

What we claim as new and desire to secure by Letters Patent of the United States, is,—

1. A machine for washing blue-prints 100 and the like, comprising a plurality of parallel shafts, each provided with a plurality of disks, those on one shaft overlapping those on the adjacent shafts, and water spraying devices in proximity to said disks. 105

2. A machine for washing blue-prints and the like, comprising a series of shafts, disks arranged at intervals on said shafts,

the disks on each shaft extending into the spaces between the disks on the adjacent shaft, means for rotating said shafts in the same direction, and water spraying devices 5 in proximity to said disks.

3. A machine for washing blue-prints and the like, comprising a series of shafts having their axes in a common plane, disks secured at intervals to said shafts, the disks 10 on each shaft extending into the spaces between the disks on the adjacent shaft, means for rotating said shafts in the same direction, and water spraying devices in proximity to said disks.

15 4. A machine for washing blue-prints and the like, comprising a plurality of parallel shafts each provided with a plurality of disks, sprocket-wheels on said shafts arranged alternately in two rows, two chain-belts engaging with said rows of sprockets,

and means for spraying water above said disks.

5. A machine for washing blue-prints and the like, comprising a bank of disks rotating at a given speed, and means for 25 smoothing out the prints as they leave the said bank of disks.

6. A machine for washing blue-prints and the like, comprising a plurality of shafts all rotating at a given speed, disks on said 30 shafts increasing in diameter from shaft to shaft, and means for spraying water in proximity to said disks.

In witness whereof, we have hereunto set our hands this 13th day of July, 1904.

JOHN W. UPP.

WILLIAM O. WAKEFIELD.
